Primary Examiner — Derrick E Holland*Assistant Examiner* — Jennifer O King(74) *Attorney, Agent, or Firm* — Wolf, Greenfield & Sacks, P.C.(57) **CLAIM**

The ornamental design for an outlet cover, as shown and described.

DESCRIPTION

FIG. 1 is a front, bottom, right perspective view of the outlet cover according to my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dash-dash broken lines in the drawing depict portions of the outlet cover that form no part of the claimed design. The short dash-long dash lines in the drawings depict boundaries of the claimed design that form no part of the claimed design.

1 Claim, 7 Drawing Sheets(56)
